UNITED STATES PATENT OFFICE.

WALTER HOWARD, OF WASHINGTON, DISTRICT OF COLUMBIA.

CAR HEATING AND VENTILATING APPARATUS.

SPECIFICATION forming part of Letters Patent No. 503,745, dated August 22, 1893.

Application filed February 3, 1893. Serial No. 460,885. (No model.)

To all whom it may concern:

Be it known that I, WALTER HOWARD, a citizen of the United States, residing at Washington, in the District of Columbia, have invented certain new and useful Improvements in Car Heating and Ventilating Apparatus, of which the following is a specification, reference being had therein to the accompanying drawings.

10 My invention relates to that class of car heating and ventilating apparatus in which the air used for the purpose is taken from in front of the locomotive and is heated by the steam and hot gases produced therein; and 15 the objects of my invention are to produce simple and comparatively inexpensive means for utilizing the wasted heat and gases received in the smoke-box of a locomotive, and also the caloric produced by the exhaust steam 20 of the engine. I attain these objects by the construction illustrated in the accompanying drawings in which—

Figure 1, is a side view of a locomotive and a portion of a train of cars heated and ventilated in accordance with my invention. Fig. 2, is a side view of the front portion of the locomotive on a large scale. Fig. 3, is a longitudinal central vertical section of a portion of the locomotive. Fig. 4, is a transverse vertical section of the same on a line passing through the center of the smoke stack. Fig. 5, is a longitudinal vertical section through the floor of a car provided with means for heating and ventilating it in accordance with 30 my invention. Fig. 6, is a plan view of the under side of the car. Fig. 7, is a horizontal section of the car, above the floor thereof. Fig. 8, is a perspective view of one of the hot-air regulating register-plates to be placed 35 within the hot-air pipes to control the issue of hot-air therefrom. Fig. 9, is a longitudinal vertical section on a large scale of one end of the hot-air and steam carrying pipes, showing the steam controlling valve on the 40 latter. Fig. 10 is a transverse section of the double fan used with the apparatus. Fig. 11, represents on a large scale an inside view and Fig. 11^a a transverse section on line x x of Fig. 11 showing the lever used to control 45 from a distance the steam valve placed upon the steam pipe of the cylinder of the engine. Fig. 12, is a perspective view of the combined

feed water heater and steam reservoir for the car heating pipes. Fig. 13 is a transverse vertical section on line y y of Fig. 3.

In said drawings A represents the boiler of a locomotive suitably carried on wheels as usual, the driving cylinders B being supplied with steam from the steam dome through pipes b. The steam after it has moved the driving pistons, exhausts through suitable pipes as usual into the saddle C of the frame and thence through the pipe b' into an exhaust chamber D placed a short distance in front of the forward flue sheet A² of the boiler. 60 During warm weather the steam is allowed to escape from the top of the chamber D, through a pipe d having its upper end within the smoke stack A³ of the locomotive. But during cold weather the pipe d is closed or 65 partly closed by means of a valve d² placed upon said pipe, and the steam is conducted by means of pipes d³ issuing from each side of the chamber D into branch pipes d⁴, Fig. 4 that lead into steam pipes d⁵, that are incased 70 within air pipes E, and said pipes E with the steam pipes d⁵ in their interior extend the whole length of the train. These steam pipes d⁵ help to maintain the air in the pipes E at a high temperature. But said air is primarily 75 received into the pipes E in a warm condition. For this purpose there is placed on the front of the locomotive a fan F preferably of the form shown in my application for patent filed January 4, 1893, that receives the atmospheric 80 air through its eye and discharges it through its periphery into vertical pipe f, on each side of the locomotive, through which it is conducted into coils of pipes f² suitably supported in a smoke chamber A⁴ in the front 85 end of the boiler under the smoke stack A³. In the top of said chamber there is a plate A⁵ having a series of perforations the size of which is regulated by a similarly perforated plate or damper A⁶ adapted to be horizontally 90 reciprocated to remove the ashes accumulating thereon. From the coils f² the heated air enters the car-heating pipes E at f'. To regulate the amount of heated air directed 95 into the pipes E or to permit the whole current of air sent by the fan to be deflected directly into the pipes E, if the atmospheric air is nearly warm enough, there is placed upon the top of the vertical pipes f a cock f³.

that is then closed and a cock f^4 that is kept open adjacent to a horizontal pipe f^5 that has one end connected with the pipe f and the other end directly with the pipe E .

5 To return the sparks or cinders that fall into the bottom of the smoke chamber A^4 , back to the furnace of the locomotive, there is at the rear of the fan F a small fan G on each side of said chamber connected with the fan F by means of a belt retained under proper tension. The eye of the fan G is connected with the bottom of the chamber A^4 , and attached to its periphery there is a pipe G^2 that conducts the sparks to the furnace or fire chamber of the locomotive and thus increases the combustion in said furnace. The shaft of the fan F is rotated by means of an eccentric or crank on each end that is connected with the piston rod of a small cylinder H on each side of the boiler suitably retained against the side of the chamber A^4 . The piston of said cylinder H is operated by steam brought from the steam dome through the pipe h , and the exhaust steam is conducted from said cylinder through the pipe h^2 to the exhaust chamber D , into which it enters through the opening h^3 in the side thereof.

In very cold weather live steam is taken directly from the steam-dome of the engine through the pipe h to supply the steam pipes d^5 placed within the pipes E . For this purpose the portion of the pipe h located in front of the exhaust chamber D is extended downward under the point where it branches off toward the cylinder H , and said extension enters the pipe d^4 as shown in Fig. 2. When live steam is used the cock d^6 leading from the pipe d^4 into the exhaust chamber D is closed.

To permit the engineer to control from his cab the admission of steam to the chest of the cylinder H , there is placed upon the horizontal branch of the pipe h , a valve, the stem of which carries a cog wheel i Fig. 11 that is received between the parallel branches i^2 of a tubular lever I . The inner sides of said branches are provided with teeth, but said inner sides are placed far enough apart, that both of them cannot come simultaneously into engagement with the cog wheel i . On the side of the teeth of each branch, a flat spring i^3 is secured to the lever I at the inner end of the long slot between its branches. Said springs are so arranged with their outer end free from each other, that either one can be forced laterally and outwardly from the face of the teeth on the branch i^2 to permit engagement of said teeth with the teeth of the cog-wheel, while the opposite spring causes said engagement to take place. To force either one of the springs i^3 outwardly, there is within the tubular lever I a rod I^2 that carries on its front end a triangular cam I^3 adapted to bear against one of the springs i^3 , and on its rear end a handle I^4 to give a partial revolution to said rod and its cam.

The lever I is operated by the engineer moving it back and forth, and thereby actuating the valve of the pipe h . A lever as I and its rod I^2 can be applied to other valves of the engine if at a distance from the engineer. The heating and ventilating pipes E are provided with joints and short pipes E^2 arranged in zig-zag order near each end of each car to allow for the expansion and compression of the bumpers, said pipes E^2 containing also similarly arranged short steam pipes. The last bends of the pipes E^2 are parallel with the axis of the car.

Each car is provided with two combined steam and air pipes on each side, the pipe E^4 being placed under the floor of the car, and the pipe E^3 upon said floor, the pipe E^4 being intended mainly to convey the air and steam from one car to the other the whole length of the train; while the pipe E^3 is intended to distribute the heated air within the car. For this purpose the pipe E^3 has in its side a series of slotted openings k which can either be closed entirely, or their size regulated by means of trough like sectional plates K placed within said pipe, that have correspondingly slotted openings k^2 to coincide with the openings k when desired, and solid walls between the openings k^2 to close the openings k when said solid portions of the plate K are opposite the said openings k . The outer curved surface of the plates K is kept in close contact with the interior surface of the pipes E^3 by means of spring-arms k^3 projecting from the rear of the plates K and bearing against the opposite surface of the pipes E^3 . To slide the plates K , each one is provided with a pin k^4 projecting radially therefrom through one of the openings k^2 and said pin is pivotally connected with an angular lever k^5 carried in suitable bearings and extended horizontally within the car. Partial rotation of the plates K is prevented by guide pins k^6 projecting from the side of said plates and passing through horizontal slots in the pipes E^3 . Each pipe E^3 is also provided near each end thereof with a funnel g on top thereof to receive perfumed or disinfecting liquid, as may be desired, to be slowly introduced in said pipe, said funnel being closed by a removable cover g^2 and having a small faucet g^3 in the small pipe supporting it.

The steam pipes d^5 within the pipes E^3 are controlled at each end of the car by means of a valve d^6 within the elbow of said pipes. Said valve has its upper edge preferably hinged to a loop of metal within said elbow and is retained and operated by means of a screw-rod d^7 passing through and in engagement with said elbow and with the elbow of the pipe E^3 , the ball-shaped head of the screw-rod d^7 being received in a correspondingly shaped recess within the rear of the valve d^6 . The lower air-pipes E^4 can also be controlled by similar valves d^7 .

To utilize the caloric given by the exhaust steam of the engine to the walls of the ex-

haust chamber D to heat the feed-water injected into the boiler as usual, said exhaust chamber has formed against its rear wall a water heating chamber D² having the same length and height, into which water is conducted from the injector through the pipe D³ and it issues therefrom near the top, into the boiler through the pipe D⁴. Said chamber D² is provided with a pipe m² to remove the sediment accumulating in the bottom thereof; and the exhaust chamber D has a pipe m to remove the water condensing in the bottom thereof.

I am aware that in heating apparatus, steam pipes have been placed within pipes used to convey air, to heat said air, and I do not broadly claim said feature.

Having now fully described my invention, I claim—

1. In combination with the forward flue-sheet of a steam boiler, the vertical exhaust chamber D in front of said flue-sheet and having a water heating chamber D² against its rear wall, a pipe d having a valve d² thereon and leading from the top of said chamber D into the smoke stack, a pipe d³ leading from the side of said chamber D into pipes d⁵ extended into a car, and air pipes E inclosing said pipes d⁵ substantially as described.

2. The combination of the forward flue sheet of a locomotive boiler, the vertical exhaust chamber D in front of said flue-sheet and having a water heating chamber D² against its rear wall, a pipe d having a valve d² thereon and leading from the top of said chamber D into the smoke stack, a pipe h leading steam from the steam space of the boiler into pipes d⁵ at the sides of said boiler and conducted into a car in the rear of said boiler, and air pipes E encircling said pipes d⁵.

3. The combination of the forward flue sheet of a steam boiler, the vertical exhaust chamber D in front of said flue-sheet and having a water heating chamber D² against its rear wall, a pipe d having a valve d² thereon and leading from the top of said chamber D into the smoke stack a pipe d³ leading from the side of said chamber D into pipes d⁵, steam pipes d⁵ at the sides of said boiler and led into a car in the rear of said boiler, a smoke chamber in front of the exhaust chamber D, coiled air pipes f² in said smoke chamber and leading into pipes E on the outside of the boiler, and air pipes E encircling the pipes d⁵ substantially as described.

4. The combination of the forward flue-sheet of a steam-boiler the vertical exhaust chamber D in front of said flue-sheet and having a water heating chamber D² against its rear wall, a pipe d having a valve d² thereon and leading from the top of said chamber D into the smoke-stack a pipe d³ leading from the side of said chamber D into pipes d⁵, steam pipes d⁵ led into a car in the rear of said boiler, a smoke chamber in front of the exhaust chamber D, a perforated plate A⁵ in the top of said smoke chamber, a perforated

damper A⁶ upon the plate A⁵, coiled air pipes f in said smoke chamber, and air pipes E encircling the pipes d⁵ substantially as described. 70

5. The combination of the forward flue-sheet of a steam-boiler, the vertical exhaust chamber D in front of said flue-sheet and having a water heating chamber D² against its rear wall, a pipe d having a valve d² thereon 75 and leading from the top of said chamber D into the smoke stack a pipe d³ leading from the side of said chamber D into train pipes d⁵, a smoke chamber A⁴ in front of the chamber D, a fan F in front of the chamber A⁴, the air pipe E leading to cars, a cylinder H having its piston connected with the shaft of the fan F, and exhaust pipe h² leading from said cylinder H into the exhaust chamber D substantially as described. 80

6. The combination of the forward flue sheet of a steam boiler, the vertical exhaust chamber D in front of said flue-sheet and having a water heating chamber D² against its rear wall, a pipe d having a valve d² thereon 90 and leading from said chamber D into the smoke stack a pipe d³ leading from the side of said chamber D into train pipes d⁵, a smoke chamber A⁴ in front of the chamber D, a fan F in front of the chamber A⁴, a cylinder H 95 having its piston connected with the shaft of the fan F, an exhaust pipe h² leading from said cylinder H into the exhaust chamber D, a live-steam pipe h for the cylinder H, a valve upon said pipe h a cog wheel upon the stem 100 of said valve, and a valve operating lever having racks for actuating said valve and extended rearwardly thereof and the pipe E to conduct the heated air to the cars substantially as described. 105

7. The combination of the forward flue-sheet of a steam boiler, the vertical exhaust chamber D in front of said flue-sheet a pipe d having a valve d² thereon and leading from the top of said chamber to the smoke stack, a 110 pipe d³ leading from said chamber D into pipes d⁵ and the latter into a car, and a feed-water reservoir D² attached to the rear wall of the exhaust chamber substantially as described. 115

8. The combination of a locomotive, steam pipes d⁵ leading therefrom to cars, a fan on the front of the locomotive, and air pipes E and E² leading to cars with pipes E⁴ under the floor of the car and pipe E³ on top of said floor, said pipes E³ having slotted perforations k and trough-like plates K within the pipe E³ said plates K having slotted perforations k² and arms k³ substantially as described. 125

9. The combination of a locomotive, steam pipes d⁵ leading therefrom to cars, a fan on the front of the locomotive, and perforated air pipes E³ within the cars, trough-like plates K within the pipes E³, steam pipes d⁵ within the air pipes, said pipes d⁵ and E³ having elbows at their ends, a valve d⁶ at the end of the pipe d⁵ and a screw valve-rod passing through said elbows substantially as described. 130

10. The combination of a locomotive, steam pipes d^5 leading therefrom to cars, a fan on the front of the locomotive and perforated air pipes within the cars, trough-like plates K within the pipes E³, steam pipes d^5 within the air pipes, and a funnel g upon the air pipes and having a removable cover and faucet substantially as described.

11. The combination of the air pipe E leading from the locomotive to the cars, the air pipes E³ and E⁴ carried by the cars, the pipes E³ being provided with perforations communicating therewith, the steam pipes d^5 extending through pipes E and E³, and the trough-like sliding plates K located within the pipes E³, substantially as described.

12. The combination of the air pipe E lead-

ing from the locomotive to the cars the air pipes E³ and E⁴ carried by the cars, the pipes E³ being provided with perforations communicating therewith, the steam pipes d^5 extending through pipes E and E³, and the trough-like sliding plates K located within the pipes E³, said plates K having pins k⁴ projecting through the air pipes, and angular levers k⁵ connected with said pins substantially as described.

In testimony whereof I affix my signature in presence of two witnesses.

WALTER HOWARD.
